UNITED STATES PATENT OFFICE.

WILLIAM C. MEYER, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,017,440.

Specification of Letters Patent. Patented Feb. 13, 1912.

Application filed November 4, 1904. Serial No. 231,342.

To all whom it may concern:

Be it known that I, WILLIAM C. MEYER, a citizen of the United States, residing at Boston, in the county of Suffolk and State 5 of Massachusetts, have invented certain new and useful Improvements in Shoe-Sewing Machines; and I do hereby declare the following to be a full, clear, and exact description of the invention, such as will enable 10 other skilled in the art to which it appertains to make and use the same.

The present invention relates to an improvement in sewing machines and more particularly in sewing machines of the 15 curved hook needle, chain-stitch wax-thread type known as welt and turn machines.

In the operation of the well-known Goodyear welt and turn machine, illustrated with substantial accuracy in the patent to 20 French and Meyer, No. 412,704, dated October 8, 1889, the stitch is set by the take-up which pulls upon the loop of thread standing around the shank of the needle while the latter is in the work thereby bringing 25 the thread which forms the stitch into its final position in the seam. Inasmuch as the tightness of the seam depends upon the tension upon the thread at this time this machine in practical operation has been run 30 under as great a tension as the thread would stand, but this tension has been measured not by the liability of the thread to break at this time in the operation of the machine, but by the liability of the thread to break 35 during the last part of the retracting stroke of the needle. This is because during the thread pulling stroke of the take-up the thread extends around the soft material of the between substance and the smooth sur- 40 face of the shank of the needle while during the last part of the retracting stroke of the needle the thread is bent around and receives slightly through the small throat of the 45 needle so that with the same strain on the thread it is much more liable to break at this time. Thus it will be seen that the tension which the thread would stand during the retracting stroke of the needle determined the maximum tension which could be 50 used on the machine and precluded the use of as much tension as was desired, and in fact desirable, to be used during the operation of the take-up.

The object of the present invention is to 55 reorganize and improve the chain-stitch

sewing machine in which a take-up, or equivalent device, is employed to set the stitch while the needle is in the work, by providing the machine with an improved tension mechanism operating to subject the 60 thread to a certain tension during the time the needle is making its retracting stroke and to a certain increased tension during the time the take-up is acting to tighten the loop of thread standing around the shank 65 of the needle while it is in the materials.

Other features of the invention will be pointed out in connection with the description of the illustrated embodiment of the invention and will be specifically defined in 70 the claims.

In the accompanying drawings illustrating the preferred form of the invention, shown in connection with the well-known Goodyear welt and turn machine which is 75 illustrated with substantial accuracy in the patent referred to, only so much of the machine is shown as is necessary for a complete understanding of the present invention and the parts not herein referred to may be, 80 and preferably are, the same as in said patented machine.

Figure 1 is a side elevation of the machine, unessential parts being omitted. Fig. 2 is a rear elevation and Fig. 3 is a plan 85 showing the tension device in section.

The illustrated embodiment of the invention is described as follows:—The needle N, the take-up T, the auxiliary take-up t, the looper L, the thread finger F, the welt guide 90 G (back gage, in case of a turn machine) and back rest R are constructed, organized and operated in substantially the manner illustrated and described in said patent. The tension wheel or thread truck W is loosely 95 mounted upon the stud 1 secured in the bracket 2 projected rearwardly from and secured to the rear portion of the head H of the machine. This thread truck W may be of any usual construction, the illustrated embodiment thereof consisting of two plates 3 and 4 provided with intermeshing fingers and forming thereby a groove for the reception of the thread which disks or plates are embraced upon opposite sides by plates 5 and 6 clamped together by rivets 7. Mounted upon and secured to the thread truck W is a brake wheel 8 which is conveniently secured to the thread truck W by the rivets 7 above referred to. Felt washers 9 and 10 105 110

upon opposite sides of the thread truck and brake wheel 8 are provided to frictionally resist the rotation thereof. A washer 11 engages the felt washer 10 and is borne upon by the spring 12 which is supported by the adjusting nut 13 and held in place by the lock nut 14. The washer 11 is provided with sockets adapted to receive the rearwardly extending portions 15 of the tension releasing lever 16 pivoted at 17 to the bracket 2 above referred to. With the exception of the brake wheel 8 the foregoing construction is substantially identical with the corresponding parts in said patented machine. The tension releasing lever 16 is connected by the chain 18 with the bell crank lever 19 which in turn supports the rod 20 by which connection is had with the main shaft of the machine in the manner illustrated in the patent to La Chapelle, No. 488,505, December 20, 1892. The brake wheel 8 is adapted to be borne upon by the brake shoe 21 provided with a felt face. The brake shoe is carried by the lever 22 pivoted at 23 in a double support 24 projected upward from the tension bracket 2. The opposite end of the lever 22 is pivotally connected with a rod 25 which passes through a hole in a pin 26 carried by the arm 27 of the cam lever pivoted at 29 upon a stationary part of the machine. The cam lever is provided upon its other arm 28 with a cam roll which enters a cam path in the cam disk 30 mounted upon the main shaft 35 of the machine. The rod 25 is provided below the pin 26 with an adjusting nut 31 and a set nut 32. The rod 25 above the pin 26 is embraced by a spring 33 which bears upon the pin 26 at one end and upon a washer 34 held in place on the rod 25 by a nut 35. The nuts 31 and 35 afford means of adjustment.

It has not been considered necessary to illustrate the cam path in the cam disk 30 by means of which the supplemental tension is operated, as any person skilled in the art could construct the same from the present description without the exercise of more than the ordinary skill of the designer.

The above described arrangement is such that during the running of the machine the tension exerted upon the thread by the friction of the felt washers 9 and 10 upon the tension wheel, owing to the pressure of spring 12, is constant. This tension will be referred to as the normal tension. It determines the tension upon the thread at all times during the operation of the machine except during those times when the extraordinary or supplemental tension is exerted thereon by what will be termed the supplemental tension, which is exerted by the brake shoe 21 upon the brake wheel 8. This supplemental tension is timed with relation to the take-up so that it is exerted during the time the take-up is rising, that is to say, dur-

ing the entire thread pulling movement of the take-up. It will be observed, therefore, that the machine is provided with means for exerting a normal tension upon the thread during the retracting movement of the needle, and means for exerting an increased tension upon the thread during the time the take-up is making its thread pulling stroke.

It is to be noted that it is only essential that the normal tension be exerted upon the thread during the last part of the retracting stroke of the needle because this is the only time during its retracting stroke when the thread is liable to reeve through the throat of the needle under strain. Furthermore, it is only essential that the increased or supplemental tension be applied during that portion of the stroke of the take-up while it is acting to set the stitch.

It is to be observed that while I have described my invention as embodied in a machine in which the normal and the supplemental tension are both applied to the thread through the same tension wheel by means of two devices which, the one constantly and the other intermittently, act thereon, my invention is not necessarily limited to such construction as other forms of mechanism might be substituted therefor without departure from the invention. For example, it is not essential to my invention, viewed in its broader aspects, that the spring exerting the normal resistance to the rotation of the tension wheel should act thereon while the supplemental tension is acting. Again, it will be understood that it is within the purview of my invention entirely to dispense with the spring 12 and to provide a cam path for actuating a single tension applying device operating to apply one tension while the needle is retracting and an increased tension while the stitch setting means are acting.

In the machine of the present invention, in which there is exerted a substantial tension upon the thread during the retracting stroke of the needle, it is necessary that a tension releasing device be provided for use in removing the sewed shoe from the machine. This tension releasing device is the same as that described and illustrated in the patent to La Chapelle. It will be understood that the intermittently acting supplemental tension is exerted upon the thread only during the time the take-up is rising, and consequently that it is not exerted upon the thread when the needle is back and when the parts are in the position which they assume when the work is removed from and entered in the machine. It is apparent, therefore, that the supplemental tension device does not need connection with the tension releasing mechanism.

The present invention is not limited to the illustrated embodiment thereof, but may

be embodied in other and different forms within the purview of my invention as described herein.

What is claimed is:—

- 5 1. A chain-stitch, shoe sewing machine, having, in combination, a needle, a looper, a stitch setting take-up, a constantly acting normal tension, and an intermittently acting supplemental tension operating during
- 10 10 the stitch-setting movement of the take-up to increase the tension on the thread, substantially as described.
- 15 2. A chain-stitch, shoe sewing machine, having, in combination, a needle, a looper, a stitch-setting take-up, a normally operative tension mechanism for exerting a constant tension upon the thread during the operation of the machine, a supplementary tension mechanism operative during the setting of the stitch, and means for relieving the constant tension to remove and enter the work, substantially as described.
- 20 3. A chain-stitch, shoe sewing machine, having, in combination, a needle, a looper, a stitch-setting take-up, a tension mechanism acting to exert tension upon the

thread during the retracting stroke of the needle, and a supplementary tension mechanism acting to increase the tension exerted upon the thread during the stitch setting movement of the take-up, substantially as described.

4. A chain-stitch, shoe sewing machine, having, in combination, a needle, a looper, a stitch-setting take-up, a tension device operating to exert a uniform and relatively light tension upon the thread during the retracting stroke of the needle and an increased tension during the setting of the stitch, and means for adjusting the tension device to vary the amount of increase in the tension without affecting the uniform and relatively light tension exerted thereby on the thread during the retracting stroke of the needle, substantially as described.

In testimony whereof I affix my signature, in presence of two witnesses.

WILLIAM C. MEYER.
